UNITED STATES PATENT OFFICE.

JOSEPH C. HEINTZ, OF NEW YORK, N. Y.

ELASTIC WEBBING.

Application filed February 9, 1920. Serial No. 357,137.

To all whom it may concern:

Be it known that I, JOSEPH C. HEINTZ, a citizen of the United States, and a resident of Stapleton, S. I., city of New York, borough of Richmond, county of Richmond, and State of New York, have invented a new and Improved Elastic Webbing, of which the following is a full, clear, and exact description.

10 This invention relates to elastic webbing such as is adapted broadly for use in garments or for sleeve supporters, garters, or the like.

15 Among the objects of the invention is to provide a novel construction in which the elastic element is preferably of metal instead of rubber as ordinarily used so that the life of the article is very much prolonged over the life of rubber elastics.

20 Another object of the invention is to provide a coating or covering for the elastic element calculated to protect the same not only from the elements or other conditions tending to cause the deterioration thereof 25 by oxidation or the like, but also to constitute a positive means to limit the extension of the webbing and hence the overstrain or stretch of the elastic element.

25 With the foregoing and other objects in view, but without unnecessarily limiting the construction in the precise manners illustrated, a preferred embodiment of the invention is illustrated in the accompanying drawings, wherein similar parts are referred to in the several views by like reference characters, and in which—

Figure 1 is a plan view of a portion of the elastic webbing involved in my invention, a portion of the elastic element or elements being exposed from the coating.

Fig. 2 is mainly an edge view of Fig. 1, but with a portion of the covering broken away.

Fig. 3 is a fragmentary horizontal section indicating the nature of the device when under maximum extension.

Referring now more specifically to the drawings, I show my elastic webbing as comprising an elastic element 10 made up of spring wire with a succession of loops or bends 10^a, each bend being bounded by two

arm portions 10^b overlapping each other. The two arms for each bend or loop 10^a constitute extensions of corresponding arms of a pair of loops or bends along the opposite edge of the elastic member, and with respect to the pair of loops the two arm extensions are disposed remote from each other, while the other two and proximate arms of said pair of loops diverge and constitute extensions from the loops located on opposite sides of the loop first described. This construction assures that the wire elastic element affords ample body or frame for the structure as a whole, and that there is provided a considerable amount of stretch without overtaxing or straining the metal.

Each flexible element 10 is covered with a flexible but non-elastic sheath 11 of tubular form, the same being applied in any suitable manner upon the flexible element either during the manufacture of the flexible structure or later, and is possessed of a certain definite length with respect to the amount of stretch desired for the article. As shown for example in Fig. 3 the sheath 11, shown elongated, is adapted for the stretching of the webbing as a whole about fifty per cent beyond its normal form. During this stretching action the loops 10^a of the wire frame are contracted somewhat due to the peculiar formation of the arms 10^b, but when the sheath has been stretched to its maximum, the wire frame portion is not yet overstretched and hence is adapted to return promptly to its normal position, causing the puckering or gathering of the sheath as indicated at 11^a.

The sheath may be left loose upon the core or body 10, or it may be fastened as by stitching along parallel rows adjacent to the edges, as indicated at 12.

The construction is well adapted for being assembled parallel as shown in Figure 1, the adjacent edge portions of adjacent strips being adapted to be connected by any suitable fasteners such as stitches or links 13. These links afford flexibility for the structure not only lengthwise but in directions perpendicular to its length.

I claim:

An elastic webbing for garment support-

ers and the like, comprising a plurality of elastic elements, each element consisting of a single strip of resilient wire bent upon itself to form a flat tension spring having marginal loops at each side, the adjacent marginal loops of each element being secured together, and a tubular non-elastic flexible covering of greater length than that

of the elastic elements when they are extended adapted to loosely house the elastic elements and to be drawn into a number of uniform folds corresponding to the marginal loops of the elastic elements by contact therewith when said elastic elements are contracted.

JOSEPH C. HEINTZ.
